(57) **CLAIM**

The ornamental design for a trailer hitch bumper/step, as shown and described.

DESCRIPTION

FIG. 1 is a top perspective view of the trailer hitch bumper/step of the present invention showing my new design with the dotted lines depicting solely environmental structure and forming no part of the claimed design;

FIG. 2 is a top plan view thereof;

FIG. 3 is front elevational view thereof;

FIG. 4 is rear elevational view thereof;

FIG. 5 is bottom plan view thereof; and,

FIG. 6 is a end view thereof.
